UNITED STATES PATENT OFFICE

FREDERICK MEIHSNER, OF MANITOWOC, WISCONSIN

SKIVING MACHINE

Application filed April 2, 1931. Serial No. 527,117.

This invention relates to improvements in skiving machines.

One of the objects of the present invention is the provision of a skiving machine adapted for cutting leather on an angle, whereby two pieces of leather can be quickly and easily matched without leaving any roughened surface at the connecting point, so as to provide a perfectly smooth surface where the two pieces are connected together.

Another object of the present invention is the provision of a skiving machine for cutting leather at a predetermined angle, so that two pieces of leather can be smoothly matched and includes a yieldably mounted guard for maintaining the leather in proper position relative to the cutting knife, so that the leather will be cut at the proper angle.

Another object of the present invention is the provision of improved means in a skiving machine, manually operated for feeding the leather between the cutting blade and the yieldable guard, whereby a positive, even cut, at a predetermined angle, can be obtained, so that two pieces of leather can be readily matched without leaving any roughened seam.

A further object of the present invention is the provision of a skiving machine of the above character provided with an adjustable guard which may be readily adjusted relative to the feeder and cutting blade, so that pieces of leather of different widths may be readily fed to the cutting knife for cutting the leather at an angle.

With the above and other objects in view, the invention consists in the novel features of construction, the combination and arrangement of parts hereinafter more fully set forth, pointed out in the claims and shown in the accompanying drawing wherein:

Figure 1 is a side elevation of a skiving machine constructed in accordance with my invention;

Figure 2 is a sectional view on the line 2-2 of Figure 1;

Figure 3 is a sectional view on the line 3-3 of Figure 2; and,

Figure 4 is a detailed plan view of the front end of the machine.

Referring more particularly to the drawing, I have provided an upright standard 1 having laterally disposed base flanges 2, apertured to receive fastening screws, bolts or other similar retaining members. At the upper end of the standard, I provide an elongated member 3, formed with a longitudinal bore to receive the rotatable shaft 4. Mounted upon the outer end of this shaft 4 is a crank arm 5 connected to the shaft by means of a set screw 6. The crank arm carries a handle 7 whereby the shaft 4 can be manually rotated. On the front end of the shaft 4 there is keyed a serrated cylinder 8.

This cylinder is provided with longitudinal ribs, all inclined in the same general direction, the ribs being indicated at 9 and in the operation of the device, the cylinder is rotated in the same direction in which the ribs incline, so that the outed edges of these ribs will engage the leather, as shown in Figure 2. One side of the standard 1 is provided with a laterally apertured projection 10 and engaged with the outer face of this projection is the lower end 11 of the blade holder 12. The blade holder includes a forwardly projecting arm 13 and the body of the holder indicated at 12 is secured to one side of the elongated member 3 by means of the threaded studs 14 having nuts 15 threaded on the outer ends thereof.

The knife blade which is removably attached to the upper face of the arm 13 includes a body portion 16 having a cutting edge 17 which projects beyond the inner side of the arm 13 and is arranged directly above the cylinder 8. The blade 16 is removably attached to the upper face of arm 13 by means of the screw members 18, the heads of which engage the opposite ends of the blade, as shown in Figure 4 for securely retaining the blade in place.

Pivotedly mounted upon the side of the elongated member 3 opposite the blade holder 12 is a rockable lever 19, the lower end of which is provided with an aperture to receive a guide rod 20. One end of the rod 20 is connected to a lateral projecting lip 21 carried by the standard 1.

The other end of rod 20 extends through

the aperture in lever 19, with a nut 22 threaded thereon which can be adjusted along the rod 20 for tensioning the coil spring 23 which is mounted upon the rod and disposed between the lip 21 and the lever 19. Extending laterally from the upper end of the lever 19 is a guard arm 24, which is tapered longitudinally and transversely to form a comparatively thin outer edge 25 and a thin outer end 26. The inner edge of the arm 24 tapers slightly on an angle and is arranged directly opposite the edge 17 of blade 16. Therefore, it will be apparent that the inner edge of the guard arm 24 and the cutting edge of blade 16 both lie directly over the cylinder 8. By tapering the inner edge of arm 24, it will have a slight space at the outer end of the guard arm and at the outer end of the cutting blade to permit the leather to be readily inserted between the two members.

Attention is directed to the fact that while the lever 19 is shown as pivotally mounted upon a stud bolt 27, carried by the elongated portion 3, this stud bolt can easily be carried by the standard 1. Adjustably mounted upon the forward end of the elongated member 3 is a guide plate 28 having a longitudinal slot 29 along its lower edge, in which is positioned a set screw 30 adapted to be tightened against the outer face of the plate 28 for retaining the same in various adjusted positions relative to the forward end of the elongated member 3.

35 The guide plate 28 is provided adjacent its upper edge with a lateral extension 31 which extends outwardly away from the cylinder 8 with its upper edge in close proximity to the lower face of the guard arm 24. Therefore, 40 when a piece of leather is inserted in between the guard arm and the cutting blade, the inner edge of the leather will strike the lateral projection 31 of the guide plate to limit the inward movement of the leather.

45 From this it will be apparent that the width of the leather to be cut will be directed by the lateral projection 31. It will be apparent that the general use of this machine is for cutting off the old soles of shoes, and the 50 like, for repair, and cutting one edge of a new sole to match the remaining portion of the old sole, whereby the two pieces of leather can be quickly and easily matched together, without leaving any roughened seam.

55 In removing the old sole, it is first cut off roughly near the shank portion which forms the instep, and the remaining stub end is then passed between the cutting edge and the guard arm, and due to the angular position 60 of the cutting edge, it will provide a slanting cut, such as illustrated in Figure 3, and the inner end of the shank portion of the new sole can also be passed through in a like manner to provide a matching cut. When 65 the leather is first inserted, it is arranged

beneath the guard arm adjacent the serrated cylinder 8, and the handle 7 is then grasped and by turning the shaft 4, the cylinder 8 is rotated which will grip the lower face of the leather and urge the same against the cutting edge 17.

In most of the skiving machines in use at the present time, which are particularly adapted for cutting off the old soles of shoes and rematching a new sole thereto, the soles are passed longitudinally through the machine requiring a longer time to properly cut the leather, whereas, in this device, the leather is passed transversely between the guard arm and the cutting edge and cutting the sole pieces transversely in a very short space of time.

The two pieces of leather cut in this manner will be separated, as shown in Figure 2, one piece traveling above the blade 16 and the other piece traveling below the arm 13 and striking the inclined surface 32 of the arm to direct the same downwardly.

It will be apparent that as the leather is engaged by the cylinder and forced toward the cutting edge 17, the arm 24 will be raised upwardly, rocking the lever 19 on its pivot against the tension of a spring 23. However, as soon as the leather has passed from between the cylinder 8, and the arm 24, the tension of the spring 23 will return the guard arm to its normal position in close proximity to the outer surface of the cylinder 8.

It will be apparent from the foregoing that I have provided a simple and inexpensive skiving machine whereby different types of leather, such as sole leather, and the like, can be skived off at an angle for matching two pieces of leather together, and the operation can be very quickly carried out as previously described.

While I have shown and described the preferred embodiment of my invention, it will be apparent from the foregoing that slight changes may be made in the construction when putting the invention into practice without departing from the spirit of the same or the scope of the appended claims.

I claim:

1. A skiving machine including a standard, a rotatable shaft supported thereby, a cylinder at one end of the shaft, longitudinal parallel ribs around the circumference of the cylinder arranged on an incline and all facing in the same general direction, a knife blade supported by the standard with its cutting edge disposed above the cylinder, a pivotally mounted lever carried by the standard, a guard arm at one end of the lever in opposed relation with the cutting blade and positioned above the cylinder, a lateral lip carried by the standard, a coil spring between the lip and the other end of the lever, and means for manually imparting movement to the shaft to rotate the cylinder in the direc-

tion in which the ribs are facing, whereby to urge the material beneath the guard arm and toward the cutting edge.

2. A skiving machine including a supporting standard, a rotatable shaft carried thereby, a serrated cylinder at one end of the shaft, a crank handle at the other end of the shaft for manually rotating the same, a cutting blade carried by the standard with its cutting edge arranged above the cylinder, a pivotally mounted lever supported by the standard and having a laterally projecting guard arm arranged above the cylinder and in opposed relation with the cutting blade, a lateral lip on the standard, a coil spring normally disposed between the lip and the other end of the lever, an adjustable guide plate carried by the standard, and a lateral projecting portion at one edge of the guide plate.

20 In testimony that I claim the foregoing I have hereunto set my hand at Manitowoc, in the county of Manitowoc and State of Wisconsin.

FREDERICK MEIHSNER.
